GAME APPARATUS

Welcome Ever Brumbelow, Los Angeles, Calif.

Application June 11, 1932, Serial No. 616,705

10 Claims. (Cl. 273—119)

This invention relates to game apparatus, one of the objects being to utilize a ball confined at all times within a container and having a seat toward which it will gravitate, there being cooperating means on the ball and seat for indicating the points scored.

A further object is to provide game apparatus having means for propelling the ball away from its seat and additional means for causing the ball 10 to follow an uncertain circuitous path toward its seat.

A still further object is to provide a means outside the apparatus for actuation by the player whereby the ball-propelling means can be brought 15 into action.

A still further object is to provide a means for operating a signal when the ball is brought to a predetermined relation to its seat.

With the foregoing and other objects in view 20 which will appear as the description proceeds, the invention resides in the combination and arrangement of parts and in the details of construction hereinafter described and claimed, it being understood that changes in the precise embodiment 25 of the invention herein disclosed may be made within the scope of what is claimed without departing from the spirit of the invention.

In the accompanying drawings the preferred 30 form of the invention has been shown.

In said drawings:

Figure 1 is a front elevation of the apparatus.

Figure 2 is a section on line 2—2, Figure 1.

Figure 3 is a section on line 3—3, Figure 2.

Figure 4 is a rear elevation of the seat 35 provided for the ball.

Figure 5 is a section on line 5—5, Figure 4, a portion of the ball being shown in engagement with the seat.

Figure 6 is an enlarged plan view of the lever- 40 controlling switch.

Referring to the figures by characters of reference, 1 designates a suitable supporting structure on which is mounted an elongated housing 2 somewhat in the form of a cornucopia with 45 its walls rounded and diverging forwardly while the front end of the housing is closed by an end wall 3 which can be of transparent material, such as glass, set in a frame 4.

The bottom of the housing 2 is inclined down- 50 wardly and forwardly toward the lower portion of the wall 3 and has rounded protuberances or humps 5 on the upper surface thereof which, as shown particularly in Figure 3, will form an irregular circuitous path leading downwardly toward the wall 3. An opening 6 is provided in

the bottom of the housing and a slot 7 extends backwardly in said bottom from the opening. This opening is adapted to receive a ball, preferably hollow and of rubber, which will gravitate toward the opening. Another opening 9 is 60 provided in the wall 3 and is so located that when ball 8 is seated in opening 6 it will also seat against the margin of the opening 9.

A lever 10 is fulcrumed beneath the housing 2 as indicated at 11 and has a head 12 at its free 65 end which is normally below and spaced from opening 6.

An arm 13 moves with lever 10 and extends downwardly from its fulcrum 11. This arm is adapted to be actuated by any suitable means 70 under the control of a player located in front of the apparatus. For example, a longitudinal slot 14 can be provided in arm 13 and in this slot there can be mounted a pin 15 extending laterally from a rigid arm 16 upstanding from 75 a slide rod 17. An operating lever 18 is located in front of the apparatus and is connected at its lower end to rod 17 by a link 19.

Rod 17 can be located under a floor 20 and lever 10 and arm 16 can be located back of a 80 wall 21 extending from the floor 20 to wall 3. The lower portion of lever 18 can be used in a counter like structure 22 with the upper or handle portion of the lever extending through a slot 23. A channeled guide 24 can be mounted in 85 the structure 22 and can be provided with a switch in the form of a tongue 25 pivoted at one end, as shown at 26, while its other end is pointed, as at 27. Ratchet teeth 28 are formed on the upper surface of the tongue and are 90 adapted to be slidably engaged by a pawl 29 carried by link 30 pivotally connected to lever 18. The parts are so proportioned that when the handle 31 of lever 18 is pulled toward the 95 left in Figure 2 the pawl 29 will slip over the ratchet teeth and ultimately drop off the tongue. Thus when the movement of lever 18 is reversed the pawl 29 will ride under the tongue until it reaches a curved deflecting wall 32 at the end of the guide 24 whereupon the pawl will be elevated past the pointed end 27 of the switch tongue, which end will subsequently gravitate to position below the pawl so that the pawl can return only by passing over the ratchet teeth.

The opening 9 is surrounded on the inner side 105 by a ring 33 of insulating material in which are embedded spaced rings 34 of conductive material. Wires 35 are extended from the respective rings to a signal such as an electric bell 36.

One or more indicators, which can be in the 110

form of numbers or other characters are arranged close to the opening and can be disposed in an annular series about the opening 9, as shown particularly in Figure 1 and directly back of one of these characters are located spaced contacts 37 extending from the respective rings 34.

The ball 8 is provided in its outer surface with an indicator 38 preferably in the form of an arrow made of sheet metal which will conduct electricity. This indicator strip is flush with the outer surface of the ball and carries a character corresponding with that character back of which are located the contacts 37.

Normally the ball 8 is located in the openings 6 and 9. The player grasps the handle 31 and pulls it toward him, thereby drawing pawl 29 over the ratchet teeth 28 and causing it to drop to the bottom of the guide 24. When handle 31 reaches the position indicated at *a* in Figure 2 the lever 10 will descend to the position indicated at *a'*, this being due to the fact that rod 17 will slide rearwardly and thrust through arm 16 and pin 15 against arm 13. The player thereafter presses handle 31 quickly toward position *b* in Figure 2 and this will cause lever 10 to swing upwardly. Head 12 will strike a blow against the ball 8 and knock it rearwardly within the casing or housing 2 and during this movement pawl 29 will pass from under switch tongue 25 and be brought to position above the point of the tongue. Thus only one blow can be struck until the pawl is again brought back under the ratchet teeth, as heretofore explained. Obviously by providing a suitable check-controlled mechanism one blow only can be permitted by the deposit of a single check.

After the ball has been thrown backwardly as described and the lever brought back to its lowered position, said ball will gravitate along the bottom of casing or housing 2 between the humps or baffles 5 and finally become seated in the openings 6 and 9. The number or other character designated by the indicator will be the amount scored by the player. If the number or other character designated corresponds with that on the ball the indicator 38 will at that time be in engagement with both contacts 37, thereby completing the circuit to the signal 36 which will thus be operated. This indication of the character corresponding with that on the ball will constitute the highest possible score.

It is to be understood that various changes can be made in the construction and operation of the mechanism. One game apparatus can be used by several players in rotation or separate game apparatus can be provided in a row for several players so as to be used simultaneously. It is also to be understood that any suitable means can be employed for locking the mechanism against actuation.

What is claimed is:

1. Game apparatus including an elongated housing having an opening in the front wall thereof and in the bottom, a ball adapted to be seated simultaneously in both openings, the bottom of the housing being inclined downwardly toward the openings, means below the housing for striking the ball backwardly within the housing for gravitation to the openings, and means outside of the housing for actuating said ball-striking means.

2. Game apparatus including a housing having an apertured front wall and a bottom inclined downwardly toward said wall, there being

an annular series of characters on the wall about the opening, a ball within the housing mounted for gravitation into the opening, indicating means on the ball adapted to be exposed within the opening to designate any one of said characters, and means under the control of a player for throwing the ball backwardly within the housing away from the opening.

3. Game apparatus including a housing having an apertured front wall and a bottom inclined downwardly toward said wall, there being an annular series of characters on the wall about the opening, a ball within the housing mounted for gravitation into the opening, indicating means on the ball adapted to be exposed within the opening to designate any one of said characters, means under the control of a player for throwing the ball backwardly within the housing away from the opening, and means on the bottom of the housing for deflecting the ball during its gravitation.

4. Game apparatus including a housing having an apertured front wall and a bottom inclined downwardly toward said wall, there being an annular series of characters on the wall about the opening, a ball within the housing mounted for gravitation into the opening, indicating means on the ball adapted to be exposed within the opening to designate any one of said characters, means under the control of a player for throwing the ball backwardly within the housing away from the opening, a signal device, and means controlled by the indicator on the ball when brought to a predetermined position within the opening for actuating the signal device.

5. Game apparatus including a housing having an opening in its front wall, the bottom of the housing being inclined downwardly toward the opening, protuberances on the bottom constituting deflectors, a ball normally seated in the opening, and means under the control of an operator for unseating the ball from the opening and throwing it backwardly in the housing for gravitation between the deflectors.

6. Game apparatus including a housing having an apertured front wall and a bottom inclined downwardly toward said wall, a ball normally seated by gravity in the opening, a striking lever supported below the ball, an operating lever for actuating the striking lever, and means for controlling the actuation of the operating lever.

7. Game apparatus including a housing having an apertured front wall and a bottom inclined downwardly toward said wall, a ball normally seated by gravity in the opening, a striking lever supported below the ball, an operating lever for actuating the striking lever, means for controlling the actuation of the operating lever, said means including a pivoted switch tongue at one end having ratchet teeth on one surface, a guide extending under and forwardly past the free end of the tongue, and a pawl carried by the operating lever and slideable along the tongue in one direction over the ratchet teeth and in the opposite direction beneath the tongue.

8. Game apparatus including a housing having a wall with an aperture, there being an annular series of characters adjacent to the aperture, a freely movable ball, means for projecting the ball into the housing, means for guiding the ball for gravitation within the housing and against the wall for exposure through said aperture, there being an indicator on the surface of the ball and a character on the ball corresponding with one of the characters of the series.

9. Game apparatus including a housing having an apertured wall, there being an indicator displayed adjacent to the wall of the aperture, a freely movable ball, means for projecting the ball into the housing, means for guiding the ball for gravitation within the housing and against the wall of the aperture, there being indicating means on the surface of the ball adapted to appear in the aperture in any one of a series of positions relative to the indicator. 80
10. Game apparatus including a housing having a wall with an aperture, there being a series of markings extending around the aperture, a freely movable ball, means for projecting the ball into the housing, means for guiding the ball for gravitation within the housing and against the wall to expose a portion of the ball through the aperture, the surface of the ball being provided with an indicator for exposure within the aperture in any one of a series of positions relative to the markings. 85
